UNITED STATES PATENT OFFICE

124,558

DESIGN FOR A DUPLICATING MACHINE

Rheinhold Thur Schmidt, Chicago, Ill., assignor
to Ditto, Incorporated, Chicago, Ill., a corpora-
tion of West Virginia

Application October 11, 1940, Serial No. 95,762

Term of patent 7 years

To all whom it may concern:

Be it known that I, Rheinhold Thur Schmidt, a citizen of the United States, residing at Chicago, in the county of Cook and State of Illinois, have invented a new, original, and ornamental Design for Duplicating Machines, of which the following is a specification, reference being had to the accompanying drawing, forming part thereof.

Fig. 1 is a perspective view of a duplicating machine embodying my new design; and

Fig. 2 is an end elevational view of the machine. The opposite side of the machine is substantially the same in appearance as the side shown except for the difference incident to the presence of the handle at the near side.

I claim:

The ornamental design for a duplicating machine, as shown and described.

R. THUR SCHMIDT.
